UNITED STATES PATENT OFFICE.

WILLIAM DOWLING, OF NEW YORK, N. Y., ASSIGNOR TO GOLDING BROS. COMPANY, OF NEW YORK, N. Y., A CORPORATION OF NEW YORK.

DESIGN FOR A TEXTILE FABRIC.

• 60,905.

Specification for Design. Patented Apr. 25, 1922.

Application filed January 4, 1922. Serial No. 40. Term of patent 7 years.

To all whom it may concern:

Be it known that I, WILLIAM DOWLING, a subject of the King of Great Britain, residing at New York, in the county of New York and State of New York, have invented a new, original, and ornamental Design for a Textile Fabric, of which the following is a specification, reference being had to the accompanying drawing, forming a part thereof.

The figure is a side elevation of a section of the textile fabric.

I claim:

The ornamental design for a textile fabric, as shown.

WILLIAM DOWLING.
